Attorney:

UNITED STATES PATENT OFFICE.

FRANCIS A. PEEBLES, OF SEVILLE, OHIO.

FENCE-POST.

SPECIFICATION forming part of Letters Patent No. 700,077, dated May 13, 1902.

Application filed December 30, 1901. Serial No. 87,797. (No model.)

To all whom it may concern:

Be it known that I, FRANCIS A. PEEBLES, a citizen of the United States, residing at Seville, in the county of Medina and State of Ohio, have invented certain new and useful Improvements in Fence-Posts; and I do declare the following to be a full, clear, and exact description of the invention, such as will enable others skilled in the art to which it applies to make and use the same, reference being had to the accompanying drawings, and to the letters of reference marked thereon, which form a part of this specification.

This invention relates to new and useful improvements in fence-posts, and especially to a metallic post used in connection with various kinds of wire fences and without slots or apertures which weaken posts; and it consists, in connection with the post, of resistance-plates, one of which is fastened to the bottom of the post, being held thereto in any suitable manner, while a second plate with preferably double-concave walls is secured to the post on its opposite edge and at a location near the surface of the ground.

Other features of the invention will hereinafter appear and will be fully described and illustrated in the accompanying drawings, in which—

Figure 1 is a perspective view of a post embodying my improvements. Fig. 2 is a detail view of the upper resistance-plate. Fig. 3 is a detail view of the resistance-plate, which is fastened to the lower end of the post; Fig. 4, a vertical sectional view through the bottom of the post.

Reference now being had to the details of the drawings by letter, A designates a metallic post, preferably of the general shape shown and imperforate, there being no slots or apertures to weaken the post. The lower end of the post rests upon the shoulder C of the resistance-plate D. Said plate D has its lower end brought to a point, and when fastened to the post projects below the lower end thereof. One face of said plate D is convexed, as at D², while its other face is concaved, as at D', and is apertured, as at d, to receive the bolt F, one end of which is adapted to en-

gage over the edge of the post, while its other end, which is threaded, receives a tightening-nut G. Said plate D is notched, as at H, to receive the post edgewise, and the outer edge of the post is flush with the tapering edge of plate D.

The second resistance-plate K has its opposite faces concaved, one face K' having two notches or grooves L opposite each other and adapted to receive the edge of the post, the opposite edge from that engaged by plate D and preferably at such a location that plate K will be near the surface of the ground when the post is lowered into a post-hole, and by reason of the other face being concaved, as shown at K², the plate K is securely prevented from moving laterally by reason of the earth engaging said concaved face K². A bolt N with one hooked end engages over the edge of the post and passes through a central aperture in plate K, and on the threaded end of said bolt N a nut N' engages side K², whereby the plate may be drawn tightly against the post, the latter engaging in said oppositely-disposed notches or grooves. By the provision of these plates secured, as described, to the post on opposite sides thereof and spaced apart the post is securely braced in all directions.

Having thus described my invention, what I claim to be new, and desire to secure by Letters Patent, is—

1. A metallic post which is imperforate, a resistance-plate having a concaved face with a shoulder at its lower pointed end, the lower end of said post adapted to rest on the shoulder of said resistance-plate, a threaded bolt with hooked end passing through said plate and holding the latter to the post and a resistance-plate fastened to the opposite edge of the post and above the plate fastened to the bottom of the post, as set forth.

2. A metallic post, a resistance-plate having a shoulder near its tapered end, a threaded bolt with hooked end passing through an aperture in said plate and designed to hold the plate to the post, said plate being concaved on one face and notched to receive the edge of the post, a resistance-plate having its

opposite sides concaved, oppositely-disposed notches or grooves on one side thereof, a threaded bolt adapted to engage over the edge of the post and designed to hold the 5 plate with concaved faces on the opposite edge of the post from that engaged by the plate at the lower end of the post, as set forth.

In testimony whereof I hereunto affix my signature in presence of two witnesses.

FRANCIS A. PEEBLES.
